PAUL DANIEL AND MAURICE MEUNIER, OF PARIS, FRANCE.

MOTOR.

SPECIFICATION forming part of Letters Patent No. 642,897, dated February 6, 1900.

Application filed June 6, 1899. Serial No. 719,537. (No model.)

To all whom it may concern:

Be it known that we, PAUL DANIEL and MAURICE MEUNIER, citizens of the Republic of France, and residents of Paris, France, 5 have invented a new and useful Improvement in or Relating to Motors, which is fully set forth in the following specification.

The present invention relates to a motor or engine with variable expansion.

10 To render the following explanation as clear as possible, we have represented, by way of example, a construction of motor according to this invention, in the accompanying drawings.

15 Figure 1 is a longitudinal section, and Fig. 2 is a cross-section, through one of the motor-cylinders.

20 The motor consists, essentially, of any number of motor-cylinders A. In the example shown there are four. These cylinders are arranged radially around a central shaft, and in each of them moves a piston B. Each piston is connected by a rod C to a fixed sleeve D, secured to the shaft D' and eccentric to the shaft D'. These connecting-rods instead 25 of being supported solely by the sleeve D are provided with shoulders, by means of which they partly fit one another. Fig. 2 clearly illustrates this arrangement. The connecting-rods C thus rest or press against the shoulders c of the adjacent connecting-rods.

30 The shaft D' is also fixed and supported at one end in the frame D'' and at the other end in the plate E, which is firmly connected to the face E' forming part of the cylinder-wall to the left of the motor, Fig. 1. The shaft on which the connecting-rods C work being fixed, it is evident that under the action of the actuating fluid within the interior of the said cylinders the latter will acquire a continuous rotary movement around the fixed 35 shaft D', and it is also evident that this movement is produced by the eccentricity of the sleeve D as regards the fixed shaft. The four cylinders are connected together into a rigid whole by means of a hoop or casing E, surrounding the ends of the cylinders and secured by fastening-screws F to shoulders c' of the cylinders. An end F' is screwed into each cylinder-head to close it, the cylinders 40 at the other end being quite open. The actuating fluid is introduced through the main inlet G, which communicates with a circular

space g around the hollow shaft g'. This hollow shaft is provided with openings g'', communicating with the annular space g. The 55 actuating fluid thus enters through these openings g'' the hollow shaft g' and thence enters the distribution-chambers by the tubes G₁, communicating with the cylinders A. Segments G'' assure the air-tightness of the joints 60 between the hollow shaft g' and the annular space g. Inasmuch as the shaft g' is rigidly united to the plate E, which turns the cylinders, this shaft g' itself turns in the bearings H, and it is therefore necessary to adjust the 65 shaft in its bearings. For this purpose we have adopted conical wedges H, provided with a screw-thread at their outer ends h. Onto these screwed parts are fitted nuts h', which are maintained in the required position by a 70 locking-plate h'', bolted to the bearing. The end of the hollow shaft is closed by a plug h''', screwed and keyed into the shaft. This plug terminates in a cylindrical part H₁, serving as the motor-shaft. The bearing H is 75 bolted onto the frame. Each tube G' communicates with the distributing-chamber of one of the cylinders.

It should be observed that in the following explanation we only give the description of 80 the working of one distribution-chamber, as they are all similar to each other.

Each distribution-chamber is divided into two very distinct parts—the first part I, into which the charge enters directly from the tube 85 G' and where the degree of expansion is regulated, and the second part I', in which the distributing device itself moves. The chamber I is connected to the chamber I' by two passages. One, represented by I₁, leads the 90 actuating-fluid under pressure from the chamber I to the chamber I'. The other, I₂, leads the exhaust from the chamber I' to the interior of the slide-valve i in the chamber I. This tube or passage I₂ is provided with a 95 branch I₃ for the escape of the exhaust. The chamber I is closed on the outer side of the distribution device by a plate J, which is common to all the distribution-chambers. On the fixed shaft D' and outside this plate 100 J is mounted an eccentric J', which can turn as regards the shaft D'. The rotation of this eccentric J is effected in the following manner: The eccentric is solidly united with a

gear-wheel j , engaging with a pinion j'' , mounted on a shaft j''' , provided at its outer end with a handle or hand-wheel J_1 . When this wheel J_1 is actuated by hand, the pinion j'' is turned, thus turning the wheel j , which turns the eccentric J' with it. It will therefore be easily understood that by simply actuating the wheel J_1 , the eccentric J' is rotated. Upon this eccentric is mounted an eccentric-collar 5 J_2 , having a connecting-rod J_3 , which serves, as will be explained, to move the slide-valve i in the distribution-chamber I. (Shown raised in Fig. 1.) For the other slide-valve i of the other distribution-chambers the connecting- 10 rods J_3 instead of being rigidly fixed to the eccentric J_2 are connected by pins or studs j_1 to the eccentric-collar J_2 . Each rod J_3 is connected by means of a stud to another rod j_2 , which in consequence of the movement of 15 the rod J_3 moves radially in a groove provided for the purpose in the plate J . This rod j_2 is provided at its inner end with a part j_3 , which completely passes through the groove or opening j_4 provided for the purpose in the 20 plate J . In this part j_3 is screwed a rod K , carrying the slide-valve i . The rod K passes through a suitable stuffing-box K' . It will be seen, therefore, that by varying the position of the eccentric J' on the shaft D' a 25 radial displacement is produced in one direction or the other of the slide-valve i . This radial displacement of the slide-valve i will effect the opening more or less quickly or the closing more or less quickly of the admission- 30 port K' of the chamber I. This, then, as it will easily be understood, is the arrangement by which the expansion is regulated. Further, to render it possible for the operator to 35 see the degree of expansion given to the engine the shaft j'' is provided at K with a screw-thread, on which a threaded nut or plate k_1 moves when the shaft j_2 is rotated, which plate actuates a pointer k_2 , moving over an indicator k_3 . Inasmuch as the displacement 40 of the nut or plate depends on the movement of the fly-wheel J_1 , one will easily understand that it is possible to graduate the indicator so that the indications given by the pointer exactly correspond to the degree of 45 expansion obtained by the position of the slide-valve i . The zero position "0" corresponds, as will be seen, to the complete closing of the port K' , and the position of the pointer at "10" will correspond to the extreme 50 opening of said port. It will therefore be possible to vary the expansion from "0" to any desired degree.

It may be observed here that the communication which exists in the interior of the slide-valve i with the exhaust serves no other purpose but to utilize the pressure of the admission fluid for applying the slide against the plate L .

Having thus described the different parts 65 by means of which the expansion is obtained, the distributing device itself will now be described.

On the shaft D' is secured an eccentric-cam L' , on which cam roll four rollers l . There is one of these rollers for each distribution-chamber. The roller l is mounted on a part l' , the shoulders of which are pressed by suitable springs l'' , having a tendency to draw the part back toward the center—i. e., toward the shaft D' . This part l' is connected to a rod l_1 , which is provided with a piston l_2 , which can be moved in the chamber I' . Within the rod l_1 a second rod l_3 can slide with slight friction, which rod l_3 is provided at its outer end with a plate or valve l_4 , which is pressed by a spring l_5 , which tends to keep it on its seat. The communication between the motor-cylinder A and the chamber I' is by way of the passage M. Let us suppose for an instant that in the way indicated above the degree of expansion has been adjusted to correspond to the movement which it is desired to obtain and let us examine the manner in which the work is carried out by the parts constituting the distribution device. Under the action of 70 the cam L' the roller l is suddenly raised at the moment required, and in this ascending movement the piston l_2 closes the exhaust-port I_2 . On the other hand, in consequence of the cushion of air at M' the rod l_3 is also 75 raised as soon as the pressure of this cushion of air exceeds that on the valve l_4 . At this moment the valve rises without any shock and the admission-fluid is free to travel from the conduit I_1 into the conduit M and from 80 there to the cylinder A. When the period of admission is ended, the length of which period is constant as regards the action of the cam, but variable by the slide-valve i , the roller suddenly descends, being also aided in 85 this descending movement by the springs l'' , mentioned above, and by the spring l_5 , which acts on the valve l_4 . The piston l_2 , descending at the same time with the rod l' , opens the exhaust, and the valve by settling itself 90 on its seat closes the admission-port. The same phases are reproduced in consecutive 95 periods as in other engines.

It should be understood that owing to the rod l_1 and the rod l_3 not being rigidly united 100 at the moment of descent of the rod l_1 the valve l_4 will have closed the admission before the exhaust orifice is opened. This condition also results from the height of the piston l_2 .

The whole device is inclosed in a casing P' , 105 perfectly tight, and connected with a condenser by means of a pipe P' .

The lubricating-oil is introduced to the interior through a pipe Q through the hollow shaft, from whence it finds its way to the various parts to be lubricated by passages q_1 q_2 q_3 q_4 q_5 q_6 , &c.

We claim—

1. In a motor, the combination of a plurality of cylinders, a stationary shaft provided 110 with an eccentric, and around which the cylinders are adapted to rotate, pistons working in said cylinders and operated from said eccentric, an admission-chamber for each cylinder.

der, an exhaust-chamber for each cylinder, a slide-valve in the admission-chamber, means for adjusting the position of the slide-valve, an admission-valve for controlling the passage 5 to each cylinder, and a piston influencing the said admission-valve, and provided with suitable operating means, substantially as set forth.

2. In a motor, the combination of a plurality of cylinders, pistons working therein, means, whereby said cylinders are enabled to rotate, admission and exhaust chambers, slide-valves in the admission-chambers, a plate rotating with said cylinders and provided with suitable radial ways, a series of rods 10 extending inwardly from said slide-valves, a suitably-supported adjustable eccentric, a loose collar on the eccentric, rods radiating from said collar, and rods guided in said ways 15 and connecting the aforesaid rods on the valves and collar, substantially as set forth.

3. In a motor, the combination of a plurality of cylinders, pistons working therein, means, whereby said cylinders are enabled to rotate, admission and exhaust chambers, slide-valves in the admission-chambers, an 20 25

adjustable eccentric, a plate in common with the admission-chambers and rotating with the said cylinders, said plate having radial ways, a series of radial connecting-rods, some of 30 which are connected with said slide-valves, others being guided in said ways, and still others being in operative engagement with said eccentric, substantially as set forth.

4. In a motor, the combination of a plurality of cylinders, pistons working therein, means, whereby said cylinders are enabled to rotate, admission and exhaust chambers, an exhaust piston and valve in each exhaust-chamber, said valve having frictional connection 35 with said piston, a fixed cam, and devices operated by said cam for operating said exhaust-pistons and thereby said valves, substantially as set forth.

In testimony whereof we have signed this 40 specification in the presence of two subscribing witnesses.
